UNITED STATES PATENT OFFICE.

SIDNEY RICHARDSON, OF LONDON, ENGLAND.

THERMOMETER AND BAROMETER.

SPECIFICATION forming part of Letters Patent No. 555,828, dated March 3, 1896.

Application filed November 22, 1894. Serial No. 529,666. (No model.) Patented in England December 15, 1893, No. 24,122.

To all whom it may concern:

Be it known that I, SIDNEY RICHARDSON, a subject of the Queen of Great Britain, residing at 356 Brixton Road, London, in the county of Surrey, England, have invented certain new and useful Improvements in Thermometers and Barometers, (for which I have obtained a patent in Great Britain, No. 24,122, bearing date December 15, 1893,) of which the following is a specification.

The first part of this invention relates to improvements in those classes of thermometers which have a single U-shaped tube, the bore of which contains mercury, spirit, acid, or other thermometric fluid, together with an index which is moved up and down within the bore to enable a register of the temperature to be kept.

The improvement consists in providing such instrument with an additional parallel bore or bores in the tube, each additional bore containing a further index, which, when accurately set, will register the temperature which the first index registered one, two, or three days previously. This part of my invention is illustrated in the accompanying drawings, in which—

Figure 1 is a face view of a Six's thermometer provided with my improvements, and Fig. 2 represents a cross-section of the tube thereof. Fig. 3 is a sectional view of the tube to show more clearly the formation of the bores. Fig. 4 is a side elevation of a barometer-tube provided with my improvement.

35 $a a'$ represent, respectively, the two parts of the thermometric bore of a single U-shaped tube containing any suitable thermometric fluid and indices $b b'$ of any ordinary or well-known description, and $c c'$ represent the two parts of an additional parallel bore made within the same tube as that containing the bore $a a'$ and containing other indices $d d'$.

The thermometric bore $a a'$ communicates with the bulb e and expansion-chamber f , and the two parts are connected together at their lower parts, being made from a single tube bent at the middle of its length, as is well understood. The part c of the additional bore is closed at its upper end—that is to say, it 45 does not communicate with the bulb e , but at its lower end it communicates with the

lower end of the part c' of the additional bore, which communicates with the expansion-chamber f .

In using such a thermometer, after the indices $b b'$ have been caused to register by the action of the temperature, the additional indices $d d'$ are made to correspond with the indices $b b'$ by a magnet, as usual. Then, on the latter moving at a subsequent period, 55 comparison can be made between such indices $b b'$ and the indices $d d'$ recording previous positions of the thermometric columns. It will be evident that my invention is equally applicable to a single straight-tube thermometer. 60

The second part of this invention (see Fig. 4) relates to improvements in that class of barometer which is provided with a single tube g , which has a bore h , containing a column of mercury i , indicating the pressure of 65 the atmosphere.

The improvements consist in providing one or two additional bores j in the tube, in each of which additional bores is placed an index k capable of being moved freely up and down 75 within the bore by aid of a magnet, which index or indices, when accurately set, enable a register to be kept of the pressure of the atmosphere of one or two days previously.

The barometer-tube is made in similar manner to that for a thermometer, the additional bore or bores being smaller than the barometric bore.

Having fully described my invention, what I desire to claim and secure by Letters Patent is—

1. A single tube for a thermometer or barometer having one or more bores additional to the thermometric or barometric bore and provided with one or more additional indices, 80 substantially as described.

2. A single barometric or thermometric tube, formed with a plurality of independent bores, provided respectively with registering devices to be set by meteorological changes and 85 registering devices to be set at will, as explained.

3. A single integral tube for the purpose set forth, containing a plurality of distinct parallel bores, and bent to form two parts, said 90 bores containing respectively a medium subject to atmospheric changes, and indicator

therefor, and indicators movable at will into position corresponding to the indication first mentioned as explained.

4. A single integral tube for the purpose set forth, having two distinct bores throughout its length, bent to form two parallel parts, and surmounted at its respective ends by a pressure-bulb respectively with which one of the bores communicates and an expansion-bulb with which both of the bores communi-

cate, said bores containing indicators as explained.

5. A single tube for a thermometer or barometer comprising the usual bore, and an additional parallel bore containing an index; substantially as described.

SIDNEY RICHARDSON.
